UNITED STATES PATENT OFFICE.

RALPH A. LEE, OF BROOKLYN, NEW YORK, ASSIGNOR TO THE BARRETT COMPANY, OF NEW YORK, N. Y., A CORPORATION OF WEST VIRGINIA.

COKING PITCH.

1,283,229.

Specification of Letters Patent. Patented Oct. 29, 1918.

Application filed April 28, 1917. Serial No. 165,093.

To all whom it may concern:

Be it known that I, RALPH A. LEE, a citizen of the United States, residing in the borough of Brooklyn, county of Kings, and State of New York, have invented new and useful Improvements in Coking Pitch, of which the following is a specification.

This invention relates to the manufacture of coke from bituminous material such as coal tar pitch and the like, and has for its objects the conversion of such material into coke by means of heat and pressure in an expeditious and highly efficient manner.

The aforesaid material, as is well known, contains varying amounts of oils and other constituents which may be vaporized by heating to obtain a coke-residue. A substantial amount of such constituents must be removed, even in the case of coal-tar pitch of high melting point, *i. e.*, hard pitch. During the heating process some of the said constituents usually break down forming new products often in part gases.

My invention has to do with results following from heating material such as coal tar pitch under pressure. It is important to note that wherever in my specification and claims I use the terms "pressure" without limitations I refer to super-atmospheric pressure.

It is well known that materials in the liquid or vapor form can be super-heated. For example, by supplying pressure a liquid can be heated above its normal boiling point, *i. e.*, its boiling point at atmospheric pressure, and still be maintained in liquid form instead of changing into vapor form. In such a case the liquid is said to be super-heated and contains a certain amount of super-heat or extra heat units. If the pressure is reduced to atmospheric, the super-heat becomes available for doing work and may act to cause the evaporation of a portion of the liquid, or to produce other effects. Also, a vapor can be super-heated so that it contains more than enough heat units to maintain it in the vapor form at a given pressure. Steam, for example, can be super-heated and if brought into contact with cooler material under proper conditions can give up some of its heat units to act on the cooler material while at the same time remaining as steam.

I have discovered that under proper conditions the super-heat, due to heating coal-

tar pitch under suitable pressure to a desired temperature is sufficient to start coking a portion of the pitch when at a less pressure. I have further discovered that as soon as the coking of pitch is begun the reaction is exothermic and is characterized by the evolution of a considerable amount of heat. In general, therefore, I heat the pitch under a pressure, for example, of 60 pounds, to a temperature preferably about that at which under such pressure it would begin to coke, say about 900° F. I then subject it to less pressure, while maintaining its container at about the same temperature as the pitch was while under 60 pounds pressure, say about 900° F. and conduct away the vapors evolved to suitable condensers. The super-heat made available by the reduction of pressure is sufficient to start the coking of a portion of the pitch and the exothermic heat from the coking reaction is sufficient to complete progressively the coking without requiring any heat from outside sources. Preferably, however, I supply a small amount of external heat to offset radiation losses and to hasten the coking operation.

In the accompanying drawings I have illustrated diagrammatically apparatus suitable for carrying out my improved process. The construction and operation of the apparatus therein illustrated is as follows:—

Coal tar pitch, for example of a melting point about 300° F. heated to a temperature of about 700° F. to 800° F. is pumped from a reservoir by means of a pump (not shown) through pipe 1 to a preheater 2. The supply pump is regulated so that the speed of the discharge of the pitch passing through the conduit 3 of the preheater is such that the pitch is maintained under a pressure of about 60 lbs. above atmospheric and heat is supplied by gas burners 4 so that the pitch is continuously heated to a temperature of about 900° F.

From the preheater 3 the super-heated pitch passes into the circulating pipe 5 which is supplied with T's as 6, to connect said pipe to one or more retorts. From the pipe 5 the heated pitch passes into branch pipe 7 through valve 8 into pipe 9 and through nozzle 10 into the coking retort 11, in which the pressure is preferably about atmospheric and around which a temperature preferably equivalent to about 900° F. is maintained by means of a heat jacket or flue 12 through

which heated gases flow to the exit chimney 13.

The super-heated pitch upon entering the coking retort 11 almost instantly separates 5 into vapors and residue upon the release of pressure. The maintenance of a temperature outside of the coking retort equal to or somewhat above the temperature within the same, by means of a heat jacket or otherwise, 10 prevents the heat liberated from escaping as a radiation loss and its activities are thus confined within the coking retort wherein it serves to volatilize certain portions of the volatile content of the pitch and also begins 15 the coking operation which is continued by a second source of heat known as "exothermic" heat, *i. e.* evolved reaction-heat. The addition of the "exothermic" heat to the heat already liberated is sufficient to complete 20 the operation and a good commercial coke is thereby produced.

The vapors liberated and produced in the retort pass through pipe 14 and valve 15 into the common vapor pipe 16 which connects 25 all retorts, where more than one is used, with a condenser 17, maintained by a suitable heat absorbing medium at such a temperature as to condense a portion of the vapors. The distillate is then drawn through 30 pipe 18 into receiver 19. Further condensers may be supplied if desired.

The uncondensed vapors or fixed gases pass through pipe 20 into a suitable gas receiver 21 which is equipped with the usual 35 water seal 22 in the well known manner.

After the charge has stopped giving off vapors, which is an indication that the coking operation is complete, the charge is dropped through door 23 that is operated 40 on a hinge 24 actuated by chain release 25 and quenched by water supplying apparatus 26.

The above description is for one retort only, but any number of retorts can be operated 45 either simultaneously or successively in series as desired.

The heating of the pitch to the desired temperature under the requisite pressure may take place in a container holding a 50 suitable quantity and the pitch may remain in the same container when the pressure is reduced or it may be conducted to another receiver coincident with reducing the pressure. I prefer to heat the pitch continuously 55 while it is being conducted under the desired pressure through a pipe and then discharge it in turn through spray or atomizing nozzles into a series of coking retorts in which the pressure is less. As soon as each retort has received a suitable charge 60 the flow is diverted to the next retort and so on. The retorts may be heavily insulated or are preferably surrounded by gases about or somewhat hotter than the retorts themselves.

65 The heat and pressure required to pro-

duce conditions suitable for working my invention will vary with the grade of pitch used. Usually pitch of a relatively low melting point, *i. e.* a soft pitch, will contain a higher percentage of volatile material 70 than a pitch of a higher melting point. This volatile material must be removed by heat to secure a coke product, and in consequence more heat will be required with a pitch of relatively low melting point than with a 75 pitch of a higher melting point. Also the pressure used will ordinarily be higher.

Having thus described my invention, what I claim and desire to secure by Letters Patent is:

1. The process of coking bituminous material liquefiable by heat, which consists in heating such material under substantial pressure to a temperature in excess of 600° F., and then reducing such pressure while 85 maintaining the materials at a coking temperature, whereby vaporizable portions are vaporized and a complete auto-coking operation is effected.

2. The process of coking bituminous material liquefiable by heat, which consists in subjecting the same to a fluid pressure in excess of atmospheric, while maintaining such material at an elevated temperature in excess of 600° F., and then materially reducing such pressure to vaporize certain 95 portions of the material and effect the coking of other portions.

3. The process of making coke from bituminous liquids which consists in heating the 100 same while subjected to a pressure of several atmospheres, to a temperature in excess of 600° F., then reducing said pressure by causing the vaporizable gases to expand in a confined space under substantially atmospheric pressure while still heated to an elevated temperature and thereby effecting the coking of portions of the material, and separating the residual coke so formed 105 from the vaporizable portions of the material.

4. The process of making coke from bituminous liquids which consists in heating the same while subjected to a pressure of several atmospheres, to a temperature in excess of 115 600° F., then reducing said pressure by causing said material to expand in a chamber maintained at an elevated temperature and under substantially atmospheric pressure and effecting the auto-coking of portions of the 120 material and separating the residual coke so formed from the vapor portions of the material in said chambers.

5. The process of coking hydrocarbon material liquefiable by heat, which consists in 125 heating such material under substantial pressure to a temperature in excess of 600° F., and then reducing such pressure while maintaining the materials at a coking temperature, whereby the liquid portions are 130

vaporized and a complete auto-coking operation is effected.

6. The process of coking hydrocarbon material liquefiable by heat, which consists in subjecting the same to a fluid pressure in excess of atmospheric, while maintaining such material at an elevated temperature in excess of 600° F., and then materially reducing such pressure to vaporize certain portions of the material and effect the coking of other portions.

7. The process of making coke from hydrocarbon liquids which consists in heating the same while subjected to a pressure of several atmospheres, to a temperature in excess of 600° F., then reducing said pressure by causing said gases to expand in a confined space under substantially atmospheric pressure while still heated to an elevated temperature, and thereby effecting the coking portions of the material, and separating the residual coke so formed from the vapor portions of the material.

8. The process of making coke from hydrocarbon liquids which consists in heating the same while subjected to a pressure of several atmospheres, to a temperature in excess of 600° F., then reducing said pressure by causing said material to expand in a chamber maintained at an elevated temperature and under substantially atmospheric pressure, and effecting the auto-coking of portions of the material and separating the residual coke so formed from the vapor portions of the material in said chambers.

9. The process of coking pitchy material which comprises heating it under pressure to substantially the temperature at which it would begin coking under such pressure, then subjecting it to a less pressure, con-

ducting away the vapors evolved, employing some of the available "pressure heat" to initiate the coking of the balance of the material and then employing substantially the available exothermic heat to complete the 45 coking operation.

10. The process which consists in heating pitchy material in a container above the boiling point of a substantial portion of its vaporizable constituents while preventing 50 such constituents from vaporizing, then materially reducing the pressure thus created, conducting away the evolved vapors and effecting the self-coking of the balance of the material treated at such reduced pressure substantially by the "pressure heat" and 55 exothermic heat.

11. The process of storing super-heat in pitchy material by heating it under pressure above the boiling point of a substantial portion of its constituents, then utilizing this 60 heat to initiate the coking of a portion of the material at a less pressure, and effecting the self-coking of a substantial portion of the material at such reduced pressure by 65 exothermic and external heat.

12. The process of storing super-heat in pitchy material by heating it under pressure above the boiling point of a substantial portion of its constituents, then utilizing this 70 heat to initiate the coking of a portion of the material at a less pressure, and effecting the self-coking of a substantial portion of the material at such reduced pressure by exothermic heat.

Signed at New York, in the county and State of New York, this 27th day of April, 1917.

RALPH A. LEE.
